COMBINED CLOCK AND WALL PLAQUE

Benjamin Levy, Hewlett, N.Y., assignor to United Metal Goods Mfg. Co., Inc., a corporation of New York

Filed Oct. 24, 1965, Ser. No. 87,892

Term of patent 7 years

(Cl. D42—7)

FIG. I

FIG.4

FIG. 2

FIG.5

FIG. 1 is a front elevational view of a combined clock and wall plaque showing my new design;

FIG. 2 is a rear elevational view thereof;

FIG. 3 is a side elevational view thereof;

FIG. 4 is a top plan view thereof; and

FIG. 5 is a bottom plan view thereof.

I claim:

The ornamental design for a combined clock and wall plaque, substantially as shown.
